LATHE-DRILL PRESS

William F. Taylor, Tulsa, Okla.

Application May 11, 1938, Serial No. 207,339
Renewed June 16, 1939

9 Claims. (Cl. 29—27)

This invention relates to a dual machine, embodying a composite lathe-drill press, which in one position constitutes a lathe, and in the other position comprises a drill press. Such is the first 5 object of this invention, that is, to provide these two kinds of machines with the same major features used in both, but occupying one position, say for the lathe, and another position for the drill press.

10 Again, this invention comprehends in the lathe structure certain convertible features relating to the headstock, the tool rest and the tailstock. Such is the second object of this invention.

Again, when the apparatus is converted into 15 a drill press it comprises, besides the main features that are also in the lathe, certain features peculiar to the drill press, as will hereinafter appear more in detail. Such is the third object of the invention.

20 Again referring to the drill, one of its important objects is to provide a raising lever and a socket within which the sphere on the support pipe fits, with the lever operable by the foot to make a vertical adjustment of the support pipe.

25 Such is the fourth object of the invention.

With the attachments shown in the drawings and described in the specification it is possible to perform a great variety of production operations with only one motor, thus accomplishing a considerable saving in shop tool investment. Such is the 30 fifth object of this invention.

Another important benefit of this combination is the conservation of floor space, an item of importance in the average workshop. Such is the 35 sixth object of my invention.

Another advantage of this combination, and a considerable one, is the fact that by its peculiar construction the conversion of the machine from lathe to drill press position is made 40 extremely easy and convenient. As a matter of fact, the counterbalance feature of this combination is one of its most important features and I believe is unique in tools of this general class. Such is the seventh object of my invention.

45 Another important object is the provision of the groove in the round support pipe and the gage assembly which make possible extreme accuracy in tailstock settings. This is essential in the lathe work. Such is the eighth object of my invention.

In the accompanying drawings:

Figure 1 is a side elevation of the essentials of a lathe with my improvements applied thereto, 50 with a portion of the tailstock in section to show

the pinion and rack cut on the surface of the quill.

Figure 2 is a side elevation of the drill press with the support pipe vertical instead of horizontal and the belt pulleys in a right angle relative 5 position.

Figure 2a is a separate view of the raising lever and its socket plate.

Figure 3 is an enlarged side view of the tailstock of the lathe with a portion in section to 10 show, on this scale, the pinion and the rack cut on the surface of the quill.

Figure 4 is a side elevation of the tailstock and the relative position of the adjusting gage block assembly. 15

Figure 5 is an enlarged side elevation of the drill press table, tailstock and drill press depth gage assembly.

Figure 6 is a right-side elevation of the hinge assembly for the combination with the assembly 20 in lathe position.

Figure 7 is an end elevation of the hinge assembly.

Figure 8 is a top plan view of the tool rest locking sleeve. 25

Figure 9 is a side view of the adjusting pinion, pinion cover and spindle.

Figure 10 is a side elevation of a part of the support pipe, in drill press position.

Figure 11 is a side view of the foot-piece and 30 the counterbalance in drill press position.

Figure 12 is a side elevation of the support pipe, the counterbalance and the foot assembly in position for conversion from drill to lathe position. 35

Figure 13 is a right side elevation of the tool rest, lock sleeve assembly.

Figure 14 is an end view of the tool rest locking sleeve assembly.

Figure 15 is an enlarged detail side view of the 40 headstock, showing more particularly the motor support plate, the pulley casing and the headstock.

Figure 16 is an end elevation of one pulley, the left end of the support pipe, the sustaining part 45 of the casing for said support pipe, and a left end view of the headstock with pulley casing in place.

Figure 17 is a top plan or bird's-eye view of the motor and the headstock, showing the relative 50 location of the support pipe and motor and also the motor support plate as well as the grooved pulleys, headstock casting and a small part of the support pipe.

Figure 18 is a left end rear view of the motor 55

support plate, the motor, the belt, the headstock spindle and the headstock casting without the pulley casing.

Figure 19 is a detail view of the motor support shown in the assembly of Figure 18.

Figure 20 is a detail plan view of the bracket which supports the motor and motor pulley.

Figure 21 is a view of the gage block assembly with the support pipe, both mounted on the tailstock, with adjusting devices in the lower part of the view.

Figure 22 is a plan view of the drill press table, showing, between two spacer lugs, the support tube with the groove.

Figure 23 is a vertical side view of parts of the drill press, namely, a section of the support pipe, a part of the tailstock with the rack and pinion, with the table which belongs to the drill press, which table may be adjusted up and down through the handle, pinion and rack, which latter screws into the table.

Figure 24 is a similar view to Figure 23 in that Figure 24 also shows a portion of the support pipe, the tailstock, and the handle, pinion and rack, with the tailstock adjusted as these parts appear in Figure 1 except that in the latter figure the tailstock element is vertical and in Figure 24 it is horizontal.

Figure 25 is a detail of the tool rest.

Figure 26 is a view of the right side of the tool rest slide and the depth-gage scale.

Figure 27 is a like view of the left side of the tool rest slide and the depth gage scale.

Figure 28 is a top plan view of the tool rest slide.

Lathe

I shall first set forth in this specification my lathe and all parts relating to it, and after this is done, I shall do likewise with respect to the drill press. And when I am dealing with the drill press, I shall bring out the features of the lathe which are utilized in the building or making of the drill.

Referring now to the lathe, it is comprised of a frame having legs 1 with a brace 2 and a strong bar 3. These parts are connected together in any conventional way, say by screws or rivets 4, 5, and 6.

On this frame is mounted the headstock 8, a single casting carrying a headstock spindle 22 (Figure 15), said headstock being secured at its lower end to the frame by bolts 10, and also carrying a casing 12 (Figure 15). Adjacent the headstock is a motor 14, the base 15 of the motor being bolted as seen at 16 to a support 17. In Figure 15, the projections 20 from the support 17 are shown with the clamping bolt and nut 21. At 18 is shown in Figure 15 the loop end of the support 17. This support is best seen in Figures 18 and 19, and extends into the loop or ring 18 which is mounted on the support pipe 19.

The support pipe 19 is a very important element in this invention. It extends, as shown particularly in Figure 1 from the ball 19a on the right to the numeral 30 on the left. This ball which adds heft to the support pipe functions in the drill press branch of this apparatus, as will be stated when we come to describe the drill press feature or part of this apparatus. The support pipe 19 also passes through a hinge arm 19b, pivoted to the bench on the hinge bolt 19c, which also functions in the drill press branch of this invention.

Figure 1 of the drawings shows that the support pipe 19 extends entirely through and beyond the headstock and its outer or left end accommodates the locking sleeve 18 on the motor support place 17. The support pipe 19 is provided with a groove 19e.

Referring back to the loop 18, it has projections 20 which are clamped together by the bolt 21 and its nut so as to bind firmly the loop 18 and the tube 19 (see Figure 18).

The headstock spindle 22 is mounted in the headstock 8 in bearings 23, 23a, 23b, three bearings. It will be seen from Figure 15 that the driven grooved pulley 24 is mounted on the headstock spindle 22 and that the driving grooved pulley 25 is mounted on the motor shaft 26. The driven pulley 24 is connected with the driving pulley 25 in Figures 15 and 17 by a V-belt 27.

In Figure 17 there is shown the motor and its housing, and also the pulleys 24 and 25. In Figure 17 there is also shown the motor 14 mounted on a plate 17 which is a part of the bracket 26a. This plate 17 goes below the motor 14 to support the motor. The slots 28 in the plate 17 are used in bolting the plate 17 to the motor 14.

The portion 18 of the bracket 26a is mounted on the end of the support pipe 19. The support pipe 19 terminates at 30 as shown in Figure 17. A bearing plate and its bolts to hold the cap are shown at 23 to sustain the left portion of the spindle 22 of the headstock. Another bearing plate, with its fastening bolts, is shown at 23a and still another bearing plate at 23b to sustain the right-hand end of the spindle 22. Part of the headstock casting 8 has notches for the bolts 10. These features are best shown in Figure 17.

Referring to the next feature of the lathe, we call attention to the tool rest 35 (Figure 1) having a spindle 36 which fits in a sleeve 37, the latter mounted on the tool holder slide 38. These devices are mounted on a clamping sleeve 39 and held by a nut and bolt 40, and having a clamping bolt 41, whereby this slide can be placed and clamped anywhere along the lathe between the headstock and the tailstock.

We turn now to the tailstock of the lathe. It is comprised of an upright casting 42 mounted at its lower end to slide to any position on the support pipe 19, to be further described presently. A conventional keybolt is indicated at 42b in Figure 1, to keep the quill 43 from turning in the tailstock 42.

The tailstock quill is designated 43 and carries within it a removable center pin 44. The tailstock 42 carries within its body an adjusting pinion 45 which meshes with a rack 46, cut on the outside surface of the quill 43. These devices are used to make adjustments of the position of the quill 43 within the tailstock with reference to the position of the spindle in the headstock. The pinion 45 is operated by the handle 47.

The tailstock 42 also carries a gage bar 47a, as seen in Figures 1, 3 and 4. This rod or bar or bolt is pivoted at 48. In Figure 4 is shown a spring 49 which merely holds the gage block 50 in contact with the support pipe 19. The gage bolt 47a carries a gage block 50 adjusted up or down by adjusting nuts 51 and the tailstock 42 has a slot 42a to give the gage block 50 access to the groove 19e. As seen in Figure 21 the tailstock is also equipped with a lock bolt 52 and its handle and with a set screw 53 which secures the handle 47 on the pinion shaft 45a.

When it is desired to use the combination as

a lathe and to do work between centers, it is essential that said centers be accurately aligned. To do this, it is merely necessary to move the tailstock 42 to such position on the pipe 19 as will enable the operator to align perfectly the center of the quill of the tailstock with the center of the spindle of the headstock. At this point the tailstock 42 is locked on the pipe 19 by the clamp 54 (Figure 21), 54 being an integral part of 42. 10 This clamp 54 is mounted on the pipe 19 and held by a nut and bolt 55. The bolt passes through lugs 56.

The gage block 50 is then adjusted by nuts 51 to snugly engage the groove 19e at which point 15 the gage block is locked by either or both of the nuts 51. The tailstock 42 may then be loosened by loosening the clamp 54 and the tailstock may then be moved longitudinally to any point on the pipe 19, and the spindle of the headstock and the 20 quill of the tailstock will be perfectly aligned with each other by re-engaging the block 50 in the groove 19e, at which point the tailstock 42 should be locked to the support pipe 19 by tightening the bolt 55.

25 Except to take up wear, no further adjustment of the gage block is necessary. Extremely accurate tailstock settings are accomplished by this mechanism, even in the dark.

Drill press

30 Thus far, I have set forth the construction and operation of the lathe branch of this invention, and will now turn to the drill press branch in the construction of which the major parts or elements of the lathe will be utilized, but will occupy a different position as seen in Figures 2 and 5, which figures have been enumerated in the list of figures composing all the drawings.

To avoid confusion, I shall employ different 40 reference numerals to designate the parts as they appear in the drill press branch as distinguished from the numerals used in connection with the lathe branch.

In Figure 2, showing the drill press assembly, 45 the numeral 70 designates the support pipe vertically standing on end, the lower end of which has a sphere 11 which rests on a bearing. Preferably this bearing consists of a base 72 adapted to be fastened to the floor or other foundation 50 by one or more bolts 73. A lever 74 is mounted at 75 and pivoted to the base 72. By placing weight, as one's foot, to the lever, I can raise and lower the support as occasion may require. The V-groove in the pipe 70 is designated by the 55 numeral 70a.

The column or support pipe 70 fits a hinge arm 76. This arm is pivoted at 77 to a bracket forming a part of the bench 78. This bench includes a leg 79 which is shown, and other suitable 60 legs, such as shown in Figure 1, being merely left off. A part of the drill press shown at 2 in Figure 1 is designated 80 in Figure 2.

In Figure 2a I have shown the base 72 and the lever 74 apart from the position of the ball. 65

In Figure 23, the numeral 70b is the tailstock casting, 70c designates the pinion, 70d indicates the spindle for the drill press table 84. The numeral 70e shows the handle. The spindle 70d has 70 a rack cut on one surface which rack meshes with the pinion 70c. The spindle 70d is permanently attached to the drill-press table 84.

In converting the lathe to the drill-press it is merely necessary to remove the quill 43 from 75 the tailstock 42, and in the hole thus vacated

insert the spindle 70d on which is permanently mounted the drill-press table 84. The lugs 84a, as shown in Figure 22, keep the table 84 in position or against losing its position when it is mounted, as seen in Figure 23, on the spindle 70d. 5

Again referring to Figure 2, the tailstock 70b is supplied with an adjusting handle 70e connected with a pinion 45 (Figure 9). This device may be used in any vertical movement that might become necessary in the use of the drill 10 table 84. Attached to the spindle 70d is this drill-press table 84. This drill-press table 84 is secured to the tailstock casting 70b (Figure 23) by means of 70d being inserted in the hole vacated by the removal of the quill 43, as stated above. 15 The drill-press depth scale 85 carries numerals 1, 2, 3 and 4, etc., as best shown in Figure 5. The depth scale slide is designated 86 and is connected to a clamp sleeve 87 by a bolt 88. This sleeve is clamped to the upright pipe 70. The upper end 20 of the pipe carries a pulley casing 89 in which is mounted one of the belt pulleys shown at 91. The part 90 is merely the foot-piece to the headstock 8.

The motor 92 is secured by plate 17 (Figure 25 20) as shown in Figure 2 to the upper portion of the pipe 70. And the pulley 94 is mounted on the motor shaft as seen at 95. This pulley 94 is the pulley used in connection with the lathe, designated 25 in Figure 15. A belt 96, the same as 30 the V-belt 27 in Figure 18, connects the pulley 94 and the headstock pulley 91.

In Figure 28 I show a top plan view of the 35 same tool rest slide as is shown in Figures 26 and 27 with its lock-bolt device 97.

Thus it will be seen that vital and indispensable parts of the lathe constitute the major parts in the drill press, as this invention comprehends a lathe-drill press entirety.

My drill reverses the usual procedure in drill 40 press practice, that is, my machine moves the work into the drill. The usual practice is to move the drill down to the work. I find that my method reduces vibration inherent in a work spindle operating in a quill. I explain this by 45 the fact that high drill spindle speeds set up a vibration which is transmitted to the movable quill which, being loose in its seat, magnifies this vibration. In my form of drill press, the tool is supported more firmly and has therefore 50 less tendency to "whip," a very serious drawback in present drills when used at routing speeds, which are very high.

Note the simple method of attaching the motor on the left end of the support pipe. By 55 merely placing the clamping sleeve 18 on the support pipe 19 and connecting the headstock and motor pulleys by belt 27, the motor, in lathe position, "floats" or maintains an automatic tension on the belt. In changing to the 60 drill press position it is only necessary to tighten the clamp bolt 21, Figure 19, to have a fixed belt tension. My form of lathe can easily be changed to turn "outboard" turnings by merely 65 changing the motor support plate 17 to the right end of the headstock 8.

It will be understood that the above-described structure is merely illustrative of the manner in which the principle of my invention may be 70 utilized, and that I desire to comprehend within my invention such modifications as come within the scope of the claims and the invention.

Having thus fully described my invention, what 75

I claim is new and desire to secure by Letters Patent, is:

- 5 1. In a dual machine, lathe parts comprising a tailstock, a quill mounted therein, a support pipe on which the tailstock is mounted, said pipe having a longitudinal slot, a gage bar mounted in the tailstock and a gage block carried by said bar and adapted to enter said slot, a rack integral with the quill and adapted to adjust the quill back and forth, and an operable pinion mounted in the tailstock and adapted to engage with said rack.
- 10 2. In a dual machine, drill press parts comprising a support pipe, a base at the lower end of the pipe, a lever to raise the support pipe from the base, and an upper support for said pipe, to keep it in a substantially vertical position, a drill press table, and a scale mounted movably on said pipe.
- 15 3. In a dual machine, lathe and drill press parts comprising a bench common to the lathe and to the drill press, a support pipe also common to the lathe and drill press and adapted to be vertically positioned in the drill press and having a support at its lower end, comprising a lever to raise the support pipe, and a base to receive the pipe.
- 20 4. In a dual machine, the combination with a bench, a support-pipe having a longitudinal slot, a tailstock having a gage-bar secured thereto and having a gage-block adapted to engage or enter said slot to maintain the tailstock from losing a vertical position, such features constituting lathe elements; of a pivot-joint between said bench and said support-pipe, a weight on the adjacent end of said support-pipe, and a base mounted near the bench and adapted to receive said weight, said support-pipe being sustained in a vertical position by said weight and said base, such features constituting drill elements.
- 25 5. A combination lathe and drill press including a longitudinal support member, a pivoted bracket to slidably receive said member, a head stock fixed to said support at one end, and a counterweight fixed to said support at the other end to counterbalance the weight of said headstock in tilting the bracket and the support member in changing from lathe to drill press, combination tailstock and drill press table mounted on said support between said bracket and headstock.

port member in changing from lathe to drill press.

6. A combination lathe and drill press including a longitudinal support member, a pivoted bracket to slidably receive said member, a head stock fixed to said support at one end, a counterweight fixed to said support at the other end to counterbalance the weight of said headstock in tilting the bracket and the support member in changing from lathe to drill press, and combination tailstock and drill press table mounted on said support between said bracket and headstock.

7. A combination lathe and drill press including a longitudinal support member, a pivoted bracket to slidably receive said member, a head stock fixed to said support at one end, a counterweight fixed to said support at the other end to counterbalance the weight of said headstock in tilting the bracket and the support member in changing from lathe to drill press, and combination tailstock and drill press table mounted on said support between said bracket and headstock and having means thereon to raise and lower such table to move the work.

8. A combination lathe and drill press including a longitudinal support member, a pivoted bracket to slidably receive said member, a head stock fixed to said support at one end, a counterweight fixed to said support at the other end to counterbalance the weight of said headstock in tilting the bracket and the support member in changing from lathe to drill press, combination tailstock and drill press table mounted on said support between said bracket and headstock and a groove along said support to align said headstock and tailstock.

9. A combination lathe and drill press including a longitudinal support member, a pivoted bracket to slidably receive said member, a head stock fixed to said support at one end, a counterweight fixed to said support at the other end to counterbalance the weight of said headstock in tilting the bracket and the support member in changing from lathe to drill press, said support member being rotatable in said bracket to face the drill press in the desired direction.

WILLIAM F. TAYLOR.
